LOCK FOR HANDBAG FRAME MEMBERS

Friedrich Pohlig, Tobyhanna, Pa.

Application March 18, 1950, Serial No. 150,481

1 Claim. (Cl. 292—128)

1

This invention relates to locks for hand bag frame members, and the like, particularly intended for use with ladies' bags.

The particular improvement consists in making the known locking device support, a part of the locking device, so that in case of repair or replacement this may be readily carried out without the difficulties attendant the known forms.

The invention consists in having a locking device supporting member on one frame member to form part of the locking device, which supporting member acts to support a sleeve controlled by a spring disposed between a platform on said supporting member and the locking cap provided with a pin pivotally engaging the sleeve, which cap engages an abutment on the other frame member to hold the frame members in closed position, and which cap on its rotation is disengaged from the abutment, to enable the frame members to separate.

The invention will be further described, embodiments thereof shown in the drawings, and the invention will be finally set forth in the claim.

In the accompanying drawings,

Fig. 1 is a partial perspective view, partially in section, of an embodiment of the invention showing the improvement;

Fig. 2 is a horizontal section showing the locking device in locked position;

Fig. 3 is a vertical section taken on line 3—3 of Fig. 2;

Fig. 4 is a horizontal section taken on line 4—4 of Fig. 3, such as shown in Fig. 2, but with the locking device in a position to enable the bag frame members to be separated or opened;

Fig. 5 is a front view of the improved locking device; and

Fig. 6 is a horizontal section of an alternative embodiment.

Similar characters of references indicate corresponding parts throughout the various views.

Referring to the drawings, the known frame members 10 and 11 are hinged to each other in a manner known and not shown.

To the frame member 11 there is secured a supporting member 12 by having its lower end or ends pass through openings 13 in the frame member 11, and then upsetting in rivet fashion said ends, as at 14 (Fig. 3). The supporting member 12 has a vertical portion 15 and a platform portion 16, to which a sleeve portion 17 is secured, or made in one piece therewith. The bore 18 of the sleeve portion 17 is engaged by a spindle portion 19 forming part of a cap or knob 20. A washer 21, preferably with an upset rivet 22, holds

2

the spindle or pintle portion 19 within the bore of the sleeve portion 17 (Fig. 3).

A helical spring 25 has one end 26 bent to engage the platform 16, to be substantially secured thereto, and has its convolution 27 surround the cylindrical portion 17 and has its end 28 engage a recess 29 in the cap 20.

The cap 20 extends from one frame member 10 to the other frame member 10, bridging the gap between.

The frame member 10 has an abutment 30 secured thereto at a longitudinal spaced position in respect to the pivot 19. The cap has an arm 31 to engage the abutment 30, when the cap 20 is in one position. When the cap 20 is rotated in respect to the pivot 19, in the direction of the arrow 33 (Fig. 4), the arm 31 becomes disengaged from the abutment 30 and the abutment with its frame member 10 may be moved in the direction of the arrow 34. The displaced position of the cap is shown in dotted lines. This enables the frame members 10 and 11 to separate, and the same to be opened.

The cap 20 has another arm 35 with an inner surface 36 which is parallel to and contiguous to the outer surface 37 of the platform 16, and this contiguity prevents the cap 20 being rotated in a direction opposite to the arrows 33.

The swinging of the cap 20 in the direction of the arrows 33 is limited by the inner surface 38 of the cap abutting against the outer corner surface 39 of the platform 16.

The platform 16 at its front has a rounded or arcuate protuberance 16a, a portion of which acts as a cam for the abutment, and the arm 31 has a cam surface 31a for the abutment 30 to enter. The inner surface 31b of the arm 31 is slightly inclined to the front plane of the wall 16b of the platform 16, and the inner tip of the arm 31 contacts with the periphery of the abutment below the diameter of abutment one end of which contacts with the curved portion 16a. The abutment 30 is thus held between the curved surface 16a and the arm 31.

An alternative construction is shown in Fig. 6, in which the longitudinal length of the cap 20a is transverse to both frame members instead of the longitudinal length being aligned with the frame members, as in Fig. 4. The parts, shown in Fig. 6 are like the parts described, excepting that spring 25a, like the spring 25, now has its free end abut against a pin 40 on the frame member 11, and the abutment 30a is like the abutment 30, excepting now in line with the pivot 19. The cap 20a is limited in one direction of its

movement by the abutting surfaces, 41 and 42; and in the other direction by the abutting surfaces 43 and 44.

In the embodiments, the member 15 is secured directly to one frame member, and supports the platform, sleeve, the spring and the cap; and the interior surfaces of the cap abut against the platform to limit the rotary movement of the cap moving in the sleeve.

I wish it to be understood that I do not desire to be limited to the exact details of construction shown and described, for obvious modifications will occur to a person skilled in the art.

I claim:

For use with a pair of complementary frame members of a handbag, fastening means for said frame members comprising a supporting member adapted to be mounted on one of the frame members and having a platform overlying said frame member, a cap rotatably mounted on the platform and having a recessed bottom portion defining a skirt, said skirt rotatably encompassing the peripheral edges of the platform and being adapted to abut said edges to limit the rotation of the cap in one direction and prevent rotation thereof in an opposite direction, said skirt having one wall thereof formed with an opening to define

a pair of arms, one of said arms being slightly hook shaped and having a free end engageable at its inner surface with an abutment adapted to be disposed on the other of said frame members, the outer surface of the end defining a cam engageable with the abutment to rotate the cap against the urging of the spring as the frame members are brought together, the abutment riding over the cam surface and being engaged by the inner surface of the end of said arm, and an arcuate protuberance formed on the edge of the platform confronting the arms, said protuberance being positioned on the edge so that it clampingly engages the abutment with the arm at a point below a line drawn diametrically through the center of the protuberance and transversely of the cap.
